OF PARIS, FRANCE

APPARATUS FOR THE MANUFACTURE OF SMOKELESS FUEL

Application filed June 22, 1926, Serial No. 117,851, and in France June 27, 1925.

This invention relates to an apparatus for the heat treatment of coal and it comprises a plurality of heating or distillation chambers with a distributing valve so constructed as to permit controlling the flow of heating fluid through the chambers in a simple and systematic way.

In our apparatus we provide a distributing valve comprising a hollow outer cylindrical member having ports in the periphery thereof and an inner cylindrical rotatable member closely fitting the inner surface of the outer member. The inner member is provided with channels therein. The terminal 10 openings of the channels register with the ports in the outer member as will be more fully described in an advantageous embodiment of our invention. Conduits connect the 15 ports in the outer member of our distributor with the inlets and outlets of the heating chambers and by virtue of our construction a turn of the inner member acts to initially conduct heating fluid from its source into any one chamber and also to conduct heating fluid 20 from one chamber to the next in series.

In the appended drawings we have shown a suitable form which our invention may take.

In the drawings;
30 Fig. 1 is a vertical section of the distributing valve shown in connection with two heating chambers;

Figs. 2 and 3 are horizontal sections taken along lines 2—2 and 3—3 of Fig. 1; and
35 Figs. 4 and 5 represent more or less generally a suitable type of heating chamber with which our distributing valve may be used.

Referring more particularly to Fig. 1, we have shown heating chambers A⁸ and A⁵ in 40 association with the distributing valve. The valve comprises an outer, stationary element h in the form of a hollow cylinder, the periphery of which is provided with equally spaced ports b¹, a¹, b⁵ and a⁵, passing through 45 the cylinder wall. Actually there are two sets of equally spaced ports arranged around the cylinder wall, one above the other.

Fig. 2 shows the lower series of ports, a¹ to a⁸ and Fig. 3 indicates the upper series 50 of ports, b¹ to b⁸. Conduits k¹ to k⁸ connect ports a¹ to a⁸ with the lower part of the heating chambers A¹ to A⁸ respectively and conduits l¹ to l⁸ connect the upper series of ports b¹ to b⁸ with the upper portions of the chambers A¹ to A⁸ respectively as shown. The flow of heating fluid through these communicating ports, conduits and chambers will presently be described in detail.

Within the outer member h, we provide a rotatable cylindrical member g which makes a gas tight fit with the inner wall of member h. In the rotatable member which is otherwise solid, we provide channels terminating in the openings c¹ to c⁸ and d² to d⁷ inclusive, as shown. The "c" openings are equally spaced to register with the "a" ports in the wall of the cylinder h and the "d" openings are equally spaced to register with the "b" ports in cylinder h upon an appropriate adjustment of the position of inner member g.

A main inlet channel c in the bottom of the inner member allows heating fluid to enter the member and since g is rotatable, we provide a conduit e pivoted at e¹ which connects inlet c with a source of heating fluid 70 advantageously superheated steam or an inert gas.

A main outlet f, pivoted at f¹, takes heating fluid from the inner member through channel d therein.

The operation of the distributing valve is as follows:—

Assume that the position of the inner rotatable member g is that shown in the drawings. Heating fluid enters the central portion of the distributing valve through main inlet duct c (see Fig. 1 for clearness) and is conducted by main channel c to the opening c¹ in the face of the inner member. The fluid passes through c¹, a¹ (the port in cylinder h) and thence by conduit k¹ into the heating chamber A¹, containing a charge of coal advantageously in briquette form. Referring to Fig. 3, the heating fluid circulates through the chamber A¹ in the direction of the arrows 85 and leaves chamber A¹ by conduit l¹, which communicates with the port b² on the outer stationary member h. The heating fluid passes through b² and d² and thence downwardly through the inner member and, by 90

100

means of the terminal opening c^2 , the port a^2 and the conduit k^2 , passes into the heating chamber A^2 . Fig. 1 shows the channels in the inner cylindrical member somewhat better, one of them being indicated by the terminal openings d^5 and c^5 . When the heating fluid has passed through chamber A^4 in the series, it leaves that chamber by conduit l^4 enters the inner member of the distributing valve through port b^5 and terminal opening d^5 , thence passes downwardly through the channel and is conducted to chamber A^5 through terminal opening c^5 , port a^5 and conduit k^5 .

In this manner the heating fluid passes through all but two of the chambers in series, finally leaving chamber A^8 through port b^7 , d^7 , and main outlet channel d (see Fig. 1).

In this construction the arrangement of ports, conduits, and channels is such that, during the heating, two chambers will be out of the heating circuit. At the instance under consideration, after the two adjacent chambers A^7 and A^8 are loaded and unloaded respectively, the rotatable member g is rotated counterclockwise so that the heating fluid initially enters chamber A^2 , and thence through chambers A^2 to A^7 inclusive, leaving the latter through main outlet duct f . During this heating cycle chamber A^8 will be loaded and chamber A^1 unloaded. In this manner each of the chambers is finally brought up to final heating temperature, that is, the temperature of the entering heating fluid.

Conduit f connects with a condensing device, not shown, to condense condensable vapors driven out of the coal during the heating thereof.

It will be clear from the foregoing that we have provided a simple distributing valve arrangement whereby the flow of heating fluid through a series of heating, or coal carbonizing chambers can be readily controlled in a systematic manner. The apparatus permits a constantly increasing, though uniform, distribution of the heating fluid and as a result, the distillation of the coal can be systematically regulated in accordance with the best conditions for any particular variety of coal.

Our distributing valve may be associated with various types of heating chambers. One advantageous form thereof is shown in Figs. 4 and 5 which, as stated, represent a suitable construction more or less diagrammatically and require no further explanation. The art is familiar with heating chambers of this and other types.

What is claimed is:—

1. An apparatus for the heat treatment of coal, comprising a plurality of heating chambers to contain coal to be heated, a distributing valve comprising a hollow cylindrical stationary outer member provided with two parallel series of ports, the ports being equally spaced around said cylindrical member,

conduits connecting the ports of the stationary member with the heating chambers, one series of ports and conduits being for the purpose of conducting heating fluid to the chambers and the other series of ports and conduits being for the purpose of conducting heating fluid from the chambers, and a rotatable cylindrical inner member disposed within the stationary member, said rotatable member and stationary member having a common axis, said rotatable member having separate channels therein, each of the channels terminating at the opposite ends thereof in opening in the cylindrical surface of the rotatable member, the channel openings at one end of said channels being spaced to register with one series of ports in the stationary member and the channel openings at the opposite end of each channel being spaced to register with the other series of ports in the stationary member, a main inlet channel to conduct heating fluid into the rotatable member, the opposite opening thereof registering with one of the ports on the outer member connected with a conduit for conducting heating fluid to the chambers, and a main outlet channel to conduct fluid from the rotatable member, the opposite opening of said channel being spaced to register with a port on the outer member connected with a conduit for conducting fluid from the chambers, whereby upon rotation of the rotatable member, heating fluid may initially pass into any one of the heating chambers and then pass through the heating chambers in series.

2. An apparatus for the heat treatment of coal, comprising a plurality of heating chambers, each having an inlet for heating fluid and an outlet for heating fluid, and a distributing valve to conduct heating fluid initially into any one of the heating chambers and then through the heating chambers in series, said distributing valve including an outer cylindrical member having two parallel series of ports, said ports being equally spaced around said cylindrical member, conduits connecting one series of ports with the inlets of the heating chambers, conduits connecting the other series of ports with the outlets of said heating chambers, a rotatable cylindrical member disposed within the outer cylindrical member, said rotatable member being provided with a series of separate channels, each of said channels at opposite ends thereof opening into the cylindrical outer surface of the rotatable member, the opposite open ends of said channels being spaced to register with the two series of ports respectively in the stationary member, whereby heating fluid may be caused to pass from one chamber to the next adjacent chamber in series.

3. A distributing valve to regulate the direction of the flow of a heating fluid through a plurality of heating chambers containing coal to be heated including a hollow cylindri-

cal stationary outer member provided with two parallel series of ports, the ports being equally spaced around said cylindrical member, and a rotatable cylindrical inner member disposed within the stationary member, said rotatable member and stationary member having a common axis, said rotatable member having separate channels therein, each of the channels terminating at the opposite ends thereof in openings in the cylindrical surface of the rotatable member, the channel openings at one end of said channels being spaced to register with one series of ports in the stationary member and the channel openings at the opposite end of each channel being spaced to register with the other series of ports in the stationary member.

In testimony whereof we have hereunto affixed our signatures.

CHARLES VIEU.
